UNITED STATES PATENT OFFICE.

DWIGHT S. COLE, OF GRAND RAPIDS, MICHIGAN.

LATCH.

1,131,826.

Specification of Letters Patent. Patented Mar. 16, 1915.

Application filed April 29, 1914. Serial No. 835,198.

To all whom it may concern:

Be it known that I, DWIGHT S. COLE, a citizen of the United States of America, residing at Grand Rapids, in the county of Kent and State of Michigan, have invented 5 certain new and useful Improvements in Latches; and I do hereby declare the following to be a full, clear, and exact description of the invention, such as will enable others skilled in the art to which it appertains to make and use the same.

My invention relates to improvements in latches, and more particularly to latches adapted for use on refrigerators, and its object is to provide a simple and effective device that will operate to insure that the door is closely and accurately closed; that will be easy of operation, simple in construction and not likely to get out of order.

The invention consists essentially of a bolt carried on a pivoted lever arranged substantially at right angles to the bolt and thence extended substantially parallel therewith and spaced apart therefrom to provide 20 a handle whereby the bolt is manually operated; a spring to hold the bolt yieldably engaged with a keeper; a keeper adapted to be attached to the casing near the door and preferably provided with a roller to engage 25 the bolt; the bolt being provided with oppositely inclined surfaces successively engaged by the keeper. The first engagement being to force the bolt inward against the action of the spring and the other inclined surface 30 adapted to engage the keeper and serve as a wedge to force the door securely to closed position by the action of the spring, as will more fully appear by reference to the accompanying drawings, in which:—

40 Figure 1 is an elevation of a latch embodying my invention; Fig. 2 a horizontal section of the same on the line 2—2 of Fig. 1; and Fig. 3 a transverse section of the same on the line 3—3 of Fig. 2.

45 Like numbers refer to like parts in all of the figures.

1 represents a portion of the casing of the door; 2 a portion of the door having an overhanging margin engaging the outer surface 50 face of the casing and closely thrust against the same by the action of the latch; 3 is a keeper of any convenient form secured to the casing opposite the bolt and preferably provided with an anti-friction roller 4 at its outer end successively engaged by the inclines on the end of the bolt when the door

is closed; 5 is a housing for the latch secured to the door and provided with outwardly projecting lugs or ears 6 at its outer end.

7 is a longitudinally movable bolt within 60 the housing having at its outer end oppositely inclined surfaces 8 and 9, the surface 9 being adapted to first engage the roller when the door is being closed and force the bolt inward to pass the roller. After this 65 surface has passed the roller the oppositely inclined surface 8 will then engage the roller and the bolt will then act as a wedge between the roller and the door to force the door closely against the casing to maintain 70 a tight joint therebetween. The bolt 7 has an inwardly extended shank 13 slidable in the inner end of the housing 5 and on this shank is a spring 12 which normally holds the bolt in extended position and forces the 75 same between the roller at one side and the door at the other side. To sustain this pressure and permit the bolt to move quite freely, the bolt is carried by the inner end 11 of a bell crank lever pivoted between the 80 lugs 6 and extending substantially at right angles to the bolt, and to near the door at its inner end wherein the bolt is pivotally supported and carried thereby. The inner end of the lever thus sustains the bolt 85 against the inward stress applied thereto by the roller 4; the outer end of the lever is preferably curved to form a handle 10 extending substantially parallel with the bolt and spaced apart therefrom and outside of 90 the housing. This handle serves as a lever fulcrumed between the ears 6 to manually move the bolt inward on passing the roller or to release the bolt from the roller when the door is to be opened, and at the same 95 time serves as a handle to open the door. This handle also can be used to force the bolt inward to cause the bolt to freely pass the roller when the door is being closed. The bolt has a limited pivotal movement in the lever, whereby its movement into and out of the casing is limited.

100 From the foregoing description the operation of my invention will be readily understood without further explanation.

105 What I claim is:—

1. A latch, comprising a keeper, a manually operated pivoted lever, a bolt carried by said lever, a spring to yieldably force the bolt into engagement with the keeper, an inclined surface on the end of the bolt to engage the keeper and force the bolt inward 110

against the spring and means for movably supporting the inner end of the bolt.

2. A latch, comprising a keeper, a longitudinally movable bolt engaging the keeper at the outer end, a housing in which the bolt is slidably supported near the inner end, a manually operable lever pivoted in the housing and carrying the outer end of the bolt and a spring to engage the bolt with the keeper.

3. A latch, comprising a keeper having a roller therein, a normally operated pivoted lever, a longitudinally movable bolt carried by said lever, a spring to yieldably force the bolt outward into engagement with the keeper, an inclined surface on the end of the bolt to engage the roller and force the bolt inward against the spring, and an oppositely inclined surface on the end of the bolt engaged by the roller to force the door to a closed position.

4. A latch, comprising a keeper adapted to be attached to a door casing and having a roller at its outer end, a housing adapted to be secured to a door, a bolt longitudinally movable in the housing, a bell crank lever

pivoted in the housing and supporting the outer end of the bolt, oppositely inclined surfaces on the end of the bolt to successively engage the roller, and a spring on the bolt to yieldably force the same into contact with the roller.

5. A latch, comprising a keeper adapted to be attached to a casing and having a roller at its outer end, a housing adapted to be secured to a door and having outwardly projecting lugs at its outer end, a bolt longitudinally movable in the housing, a bell crank lever pivoted between the lugs and having its outer end extended to form a handle and its inner end pivotally supporting the bolt, a spring on the bolt to yieldably force the same outward, and oppositely inclined surfaces on the end of the bolt to successively engage the roller.

In testimony whereof I affix my signature in presence of two witnesses.

DWIGHT S. COLE.
